FLOOR POLISHER

Carl W. Sundberg, Bloomfield Hills, Mich., assignor to
Clark-Gravely Corporation, Muskegon, Mich.

Filed May 19, 1972, Ser. No. 255,311

Term of patent 14 years

Int. Cl. D15—05

U.S. Cl. D37—3

FIG. 1

FIG. 2

FIG. 3

FIG. 4

FIG. 5

FIG. 6

FIG. 7

FIG. 8

FIG. 1 is a perspective view of the floor polisher embodying our design;

FIG. 2 is a front elevational view of the floor polisher with the upper handle broken away;

FIG. 3 is a side elevational view of the floor polisher with the central portion of the handle broken away;

FIG. 4 is the opposite side elevational view of the polisher with the upper portion of the handle broken away;

FIG. 5 is a rear elevational view of the polisher with the central portion of the handle broken away;

FIG. 6 is a top plan view of the polisher with the top portion of the handle broken away;

FIG. 7 is a cross-sectional view in block form taken along plane 7-7 of FIG. 1;

FIG. 8 is a perspective view of a modified form of the polisher embodying the design of my invention.

I claim:

The ornamental design for a floor polisher, substantially as shown and described.
